(57) **CLAIM**

I claim, the ornamental design for a percussion instrument, as shown and described.

DESCRIPTION

FIG. 1 is a top, left perspective view of a percussion instrument showing my new design;

FIG. 2 is a front, left perspective view thereof;

FIG. 3 is a top, right perspective view thereof;

FIG. 4 is a front, right perspective view thereof;

FIG. 5 is a rear elevational view thereof; and,

FIG. 6 is a bottom plan view thereof.

The phantom lines shown in FIGS. 5 and 6 are environmental and not part of the claimed design.
